UNITED STATES PATENT OFFICE.

ALLEN D. W. JOHNSON, OF ANOKA, MINNESOTA.

GRAIN BIN.

1,419,142.

Specification of Letters Patent. Patented June 13, 1922.

Application filed May 15, 1920. Serial No. 381,693.

To all whom it may concern:

Be it known that I, ALLEN D. W. JOHNSON, a citizen of the United States, resident of Anoka, county of Anoka, State of Minnesota, have invented certain new and useful improvements in Grain Bins, of which the following is a specification.

The object of my invention is to provide a grain bin of concrete block construction, 10 divided interiorly into a series of triangular bins, so arranged that the lateral pressure of the grain will be transmitted to the outside walls of the bin, provision also being made for delivering the grain from the bins to a 15 chamber beneath them or to a wagon on the outside of the structure.

A further object is to provide a bin of inexpensive durable construction and one 20 which will be fireproof and easily accessible at the top or bottom.

The invention consists generally in various constructions and combinations, all as hereinafter described and particularly pointed out in the claims.

25 In the accompanying drawings forming part of this specification,

Figure 1 is a vertical sectional view through a grain bin embodying my invention.

Figure 2 is a horizontal sectional view on 30 the line 2—2 of Figure 1.

Figure 3 is an elevation of the lower portion of the bin, showing the means for admission to the chamber beneath the bins,

Figure 4 is a sectional view on the line 35 4—4 of Figure 3.

In the drawing, 2 represents a suitable foundation and 3 the lower walls of the bin, composed preferably of concrete blocks laid one upon another in the usual way and provided with an interlocking joint 4 between 40 their longitudinal abutting edges. These lower walls are carried a suitable distance above the ground line and support a slab 5 of concrete, suitably reinforced in any preferred manner and forming the floor of the bin proper. The upper walls 6 of the bin formed in the same manner as the lower walls, rest upon the floor 5 and are carried to the desired height to form a circular bin

50 which is closed at the top by a suitable roof 7 having a central opening 8 that is normally closed by a hinged cover 9. Through this opening access may be conveniently had to the inside of the structure. The space within 55 the upper wall 6 and above the floor 5 is divided by partitions 10, 10^a, 10^b, and 10^c.

These partitions extend across the space above the floor 5, dividing it into a series of bins 11, each bin being in the form of the sector of a circle, a portion of the outer wall 60 of the structure forming one wall of the bin and two of the partitions forming the other walls. Each inner wall of a bin is laterally braced by the walls of the other bins so that when a bin is filled with grain, the lateral 65 thrust or pressure thereof will be transmitted through these partition walls to the curved outer walls of the structure and will be braced and supported thereby. The bins are provided with bars 12 at intervals having 70 their ends embedded in the partition walls and forming steps for ascending the walls of the bins or to enable a person to enter the opening in the roof of the structure and descend to the bottom of any one of the 75 bins. The floor of each bin is provided with a vertical discharge spout 13 leading to the chamber 14 beneath the bins and each spout is provided with a suitable valve 15 by means of which the flow of grain from the bins may 80 be regulated. Access to this space beneath the bins is readily obtained through the door opening 16 in the lower walls of the structure.

I also prefer to provide inclined spouts 17 85 in the walls of the structure above the floor 5 so that the material in the bins can be spouted out to a wagon box or other suitable receptacle, if desired, these spouts being equipped with suitable regulating valves 18. 90 This structure is made in various sizes and in various ways the details of construction herein shown and described may be modified and still be within the scope of my invention.

I claim as my invention:

1. A structure of the class described having a foundation and lower walls and a horizontal floor supported thereby above the lower portion of said walls forming a chamber in the base of the structure, the upper 100 walls of said structure encircling a chamber adapted to receive grain, said grain chamber having vertical partitions extending from the walls to the center thereof and dividing the interior space into a series of 105 triangular bins, said floor forming the bottom of said bins and said partition transmitting the lateral pressure of the grain in one bin to the outer walls of the structure, the floor of said bins having vertical discharge spouts therein leading to the chamber 110 beneath said floor and said chamber

having a door in its wall for access thereto, and the outer walls of said bins near said floor having outwardly and downwardly inclined spouts communicating respectively with the bins for delivering the contents thereof outside the structure to a wagon or other receptacle.

2. A structure of the class described having a foundation and lower walls and a 10 horizontal floor supported thereby above the lower portion of said walls forming a chamber in the base of the structure, the upper walls of said structure encircling a chamber adapted to receive grain, said grain chamber 15 having vertical partitions extending from the walls to the center thereof and dividing the interior space into a series of triangular bins, said floor forming the bottom of said bins and said partition transmitting the lateral pressure of the grain in one bin to the outer walls of the structure, the floor of said bins having vertical discharge spouts therein leading to the chamber beneath said floor and said chamber having a door in its wall 20 for access thereto, and the outer walls of said bins near said floor having outwardly and downwardly inclined spouts communicating respectively with the bins for delivering the contents thereof outside the structure to a

wagon or other receptacle, bars mounted in 30 said partitions in the angles between them for ascending the bins on the inside and said structure having a roof and a central opening and cover therefor through which access may be had to said bars and bins. 35

3. A structure of the class described comprising a cylindrical wall having a foundation, a flat horizontal floor supported by said wall and forming therewith a comparatively large chamber in the bottom of the structure, the upper portion of said wall having a roof and a central opening therein, and a space between said roof and floor having a series of diagonal partitions dividing it into a plurality of vertical triangular shaped bins, said horizontal floor having spouts for conducting the contents of said bins to the chamber beneath said floor and the outer walls of said structure having spouts near said floor for delivering the contents of said bin on the outside of said structure, said vertical partitions intersecting at the center of the structure and transmitting the load in said bins laterally to the outer walls thereof. 40 45 50 55

In witness whereof, I have hereunto set my hand this 4th day of May 1920.

ALLEN D. W. JOHNSON.
